CLAIM

The ornamental design for a shoe, as shown and described.

DESCRIPTION

FIG. 1 is a front perspective view of a shoe showing our new design.

FIG. 2 is a right side elevational view thereof.

FIG. 3 is a left side elevational view thereof.

FIG. 4 is a front elevational view thereof.

FIG. 5 is a rear elevational view thereof.

FIG. 6 is a top plan view thereof; and,

FIG. 7 is a bottom plan view thereof.

The long-dashed lines in the figures depict portions of the shoe that form no part of the claimed design. The short-dashed lines on the shoe upper depict stitching, which forms no part of the claimed design.

FIGS. 1-7 illustrate a left shoe showing our new design; the right shoe is a minor image and is also claimed.
